UNITED STATES PATENT OFFICE

ROSCOE E. MAJOR, OF CHICAGO, ILLINOIS, ASSIGNOR TO MAJOR EQUIPMENT CO., INC., OF CHICAGO, ILLINOIS, A CORPORATION OF ILLINOIS

ROUNDEL HOLDER

Application filed February 6, 1930. Serial No. 426,297.

This invention relates to roundel holders, such as are used in the lighting art, and more especially to releasable locking means on such holders adapted for detachable mounting of lighting accessories of roundel like character and including various kinds of lenses, shades, light diffusers, color screens and the like.

Lighting fixture accessories such as referred to are used extensively in theaters, public halls and exhibition rooms and the like, especially where reflectors are used and where color effects are desired. They are much used in connection with indirect or flood lighting and in many instances are only accessible from the rear of the fixture, as when the lights are high up on the walls or are in or near the ceiling, as in cove lighting. Roundels of various sort are commonly set each in the mouth of a bell shaped shell or lamp housing of a general type such as illustrated in the accompanying drawings.

In theatre lighting especially, the lamp housings or reflectors, usually of single lamp unit style are often placed in positions where access from the front is either impractical or not permissible. The maintenance operator can only reach such units with one hand through a special rear wall opening provided for the purpose, as will be more fully described, and he must be guided in making changes entirely by the sense of touch. For this purpose the fastener or lock must be easy to operate and must have no movable parts such as might get lost; and the lock must be entirely positive and reliable. Heretofore these needs have not been met.

The main objects of this invention are to provide an improved, simple and substantial holding device for the roundel, lens or screen; to provide a self contained and reliable mechanism of this sort with no removable parts; to provide a roundel holder construction which the maintenance attendant may gain manual access to and operate by the sense of touch; to so provide that he may then remove and replace the lens or other member and finally restore the unit as a whole to normal condition, all with one hand; to provide a lamp housing or reflec-

tor with a roundel holding rim of substantially rigid form and adapted to embracingly grip the roundel releasably by simple rotary movement; to provide for telescopic action of complementary arcuate peripheral edge gripping means; to unify the movable locking means; and to assure constant positive alignment of the coacting complementary telescopic holding members. 55

An illustrative embodiment of this invention is shown by the accompanying drawings in which:

Fig. 1 is a front elevation of a single lamp unit reflector type of roundel holder, with the lens in place and with the lock 60 closed.

Fig. 2 is a fragmentary axial section on the line 2-2 of Fig. 1, and shows the co-70 noidal bell shape of the reflector shell or roundel holder.

Fig. 3 is a fragmentary side view of the device as viewed from the left of Fig. 1.

Fig. 4 is a view similar to Fig. 2 but with the lens removed, the lock being closed.

Fig. 5 is a front elevation of the device 75 as viewed in Fig. 1 but with the fastener wide open and with the lens partly removed.

Fig. 6 is an enlarged section on the line 6-6 of Fig. 5.

Fig. 7 is a perspective view of the device 80 in its open condition and with the lens removed.

Fig. 8 is a section on the line 8-8 of Fig. 4, the lens being removed and the lock closed.

Fig. 9 is a diagrammatic view illustrating 85 how the lights and roundel holders herein referred to may be positioned and how they may be gotten at from the rear for renewals and repairs.

Referring to the drawings the lighting element or lamp, not shown, is housed in a sheet metal shell like reflector or roundel holder 1 secured at its base 2 to a support or fixture 3. The lens, color screen or other roundel accessory 4 is demountably secured 90 to the reflector rim 5 which in this instance is formed to receive the roundel 4 edgewise to enter the inwardly facing edge channel segment 6, integral with the body 1. A complementary movable channel segment 7 100

is telescopically related to the fixed segment 6, and is so proportioned relatively thereto that when moved to minimally overlie the same it will circumferentially complete the roundel holding channel and so secure the roundel in place, and when moved to maximally overlie the segment 6 the holder will be open and the roundel 4 may be removed or introduced, as will be apparent from Fig. 5.

More in detail the lock channel 6 is formed by spinning over the edge of the reflector shell 1 inwardly as shown at the lower edge of Fig. 4 and then cutting away about one hundred and eighty degrees of the cylindrical wall part 8 and corresponding outer flange part 9 as appears in Fig. 7. This form of holder freely admits the roundel 4. In order to provide for effective control and operation of the segment 7, a peripherally slidable collar 10 of sheet metal is attached to the rim of shade 1, which collar comprises the complementary channel 7.

The collar 10 is formed by spinning the inner and more restricted part to fit snugly over the corresponding edge part of reflector 1 and then spinning the outer edge part to form a channel 7 to snugly embrace the fixed channel 6. Then part of this rotary channel is removed by cutting away about half of the wall part 11 and end flange 12, as apparent from Fig. 7. The arc of the outer channel segment 7 is made somewhat greater than that of the inner segment 6, preferably about 5 to 10 degrees, so as to accommodate the stop member 13 on segment 7 and also assure substantial overlap of the channels when the lock is closed. With this in view the arc of channel 6 is preferably a little less than 180° and the arc of channel 7 a little greater than 180°.

A handle 14 is fixed on channel 7 to facilitate reciprocation thereof. This handle is carried by a small angle fitting 15 which is secured by rivet 16 passing through the wall 11 and also if desired through the stop block 13. These parts are or may be further unified by solder or brazing. The handle and stop unit is slightly spaced from one end of channel 7, so as to permit the overlap indicated at 18 on Fig. 1 when the lock is closed. The overlap on the opposite side is indicated at 19. The rearward edge of ring 10 is spun outwardly and backwardly to form a stiffening roll or bead 20.

When the lock is open the segment 7 at its stop end slightly overhangs the gap 21 of reflector 1, but the opposite end is substantially flush with the corresponding end of channel 6, as in Fig. 5. Whenever, as usual, the main axis of the reflector is inclined or horizontally disposed, the shade is positioned so that the fixed channel 6 is on the lower side, thus assuring that gravity will tend to help retain the roundel in place.

The members 1 and 10 are similarly conoidal in their mutually slidable annular parts and the member 10 is held in place on member 1 by the outer flange of channel 7 bearing on the similar flange of channel 6 and by the stop 13 bearing against the inner flange of channel 6 or such flange extended, that is to say, against the gap edge of member 1, as will be apparent from the drawings.

The device of this invention has a wide range of utility, but it is especially advantageous in cove lighting as in Fig. 9. Here the lighting unit is set in a ceiling cove 30 where the shade 1 and roundel 4 are ordinarily accessible only through a hand hole 31, or the like, in the wall or ceiling 32; the attendant being positioned on the "cat-walk" 33. In order to renew the lamp or change the roundel he has to reach with one hand through the hole 31, and guided by touch, grasp the lock handle 14 and then slide the channel ring 10 counterclockwise, as viewed in Fig. 1, to the position shown in Fig. 5. After the changes are made the reverse 90 operation is followed.

Although but one specific embodiment of this invention is herein shown and described, it is to be understood that numerous details of the construction shown and materials used may be altered or omitted without departing from the spirit of the invention as defined by the following claims.

I claim:

1. A holder of the class described comprising a plurality of normally inseparable annular coaxial members united in mutually rotary relation, each having an inwardly facing segmental arcuate channel formed edgewise thereon, said annular members being mutually nested and the channels thereof being formed to accommodate mutual telescopic adjustment for locking and for release action.

2. A conoidal lamp reflector fitted at its larger end for the interchangeable attachment of roundel means and comprising a plurality of circumferentially distributed arcuate members formed and adapted to engage the edges of the roundel means, said arcuate members being mutually slidable manually to more or less overlap for lateral opening of the engaging means whereby to accommodate edgewise admission and release of the roundel means.

3. A conoidal lamp reflector fitted at its larger end for the interchangeable attachment of roundel means and comprising a plurality of circumferentially distributed arcuate members formed and adapted to engage the edges of the roundel means, one of said members being integral with the reflector and another of said members being telescopically related thereto whereby it may be moved to overlap the same for releasing 130

the roundel means and may also be moved to supplement the said integral member for securing the roundel means in place.

4. A circular rimmed lamp reflector having on its rim a roundel holder comprising a pair of mutually supplemental and circumferentially arranged inwardly facing channel members, one of which is integral with the reflector and the other being peripherally 10 slidable to lock and to release the roundel, the latter channel member having an annular support integral therewith to slidably engage the rim of said reflector.

5. A device of the class described comprising a circular rimmed lamp reflector having a pair of mutually nested conoidal rings each formed with an arcuate inwardly facing channel, one of said rings being integral with the reflector and the other being 15 slidable circumferentially thereon to vary the mutual relation of the said arcuate channels, the movable outer channel having a stop therein adjacent to one end to limit opening and closing movement by contact 20 with the ends of the fixed channel and also prevent axial displacement of the movable ring by sliding contact with the fixed ring.

Signed at Chicago this third day of February, 1930.
